UNITED STATES PATENT OFFICE

ROBERT F. MORRISON, OF YONKERS, NEW YORK, ASSIGNOR TO THE INTERNATIONAL PAVEMENT COMPANY, OF HARTFORD, CONNECTICUT, A CORPORATION OF CONNECTICUT

PRESS

Application filed November 30, 1926. Serial No. 151,686.

This invention pertains to improvements in presses adapted for pressing materials into blocks, bricks, tiles or the like at high speed and under relatively high pressure, 5 usually known as block presses.

It is among the objects of the invention to increase the speed and smoothness of operation of such high-speed, high-power block presses while decreasing the relative upkeep 10 expense thereof.

I have elected to illustrate and describe my improvements in connection with a press of the general type shown in United States Letters Patent No. 1,003,561, issued September 19, 1911, to International Pavement Company as assignee of George E. Whitney.

In the drawings, which show one illustrative embodiment of my invention:—

Figure 1 is a side elevation of a press and 20 press-driving instrumentalities;

Fig. 2 is a plan of the press-driving instrumentalities and of the cam shaft of the press shown in Fig. 1;

Fig. 3 is a side elevation showing on a 25 larger scale the press part actuating and controlling instrumentalities secured to the cam shaft and certain cooperating parts hereinafter more fully explained.

Fig. 4 graphically represents the variations 30 in speed of the engine or cam shaft, the variations in its torque, and the time of operation of various parts of the machine during one revolution of said shaft, in one example of a machine constructed according 35 to the invention.

Referring to the drawings and to the preferred embodiment of my invention selected for illustrative purposes, I have shown (Fig. 1) a press including a hydraulic cylinder 1, 40 ejecting head 23, plunger 25 adapted to cooperate with other pressure applying instrumentalities all substantially like those shown in said Patent No. 1,003,561.

I have also shown pressure resisting columns 4, bulkheads 6, feeding neck 16, hopper 17, feed control 141, sliding head operating cylinder 124, having valve control 131, sliding head lever 116 and connecting rod 120, cooperating with a sliding head (not shown), 45 and constituting portions of molding instru-

mentalities for covering and uncovering, filling and emptying a mold or molds all generally like the molding instrumentalities shown in said patent.

The major improvements which I have made over the disclosure of said Whitney patent lie in a novel actuation of the cam or timing shaft 66 (Fig. 2) carrying the sliding head actuating cam 108, the ejecting cam 136 and the high and low pressure valve 55 cams H⁶⁵ and L⁶⁵ respectively, together with a reorganization of the relations between the movement producing or permitting surfaces 60 of these cams.

It will be noted that in the description of 65 the machine, I have thus far used numerals identical with those used for more or less closely corresponding parts in said Whitney patent, to the end that the entire mechanism of my novel press may be understood in every detail by reference to said patent in connection with this specification and drawings, 70 without unnecessarily complicating the present descriptive matter.

In the press constructed in accordance with 75 the disclosure of the Whitney patent, the cam shaft 66 is rotated by a prime mover turning at high speed, and driving a high speed worm shaft carrying a worm meshing with a worm gear on the cam shaft. The tendency of this 80 mechanism is to supply to the camshaft a substantially constant potential torque without reference to the desideratum of power required at any given portion of the revolution of the camshaft, a substantial flywheel effect 85 being supplied by the wormshaft and driving mechanism therefor. The power required of the cam shaft to move the sliding head, on the contrary, varies from a very substantial amount necessary to move the sliding head by 90 action of the cam surfaces 201 and 202 and the negligible amount, or even minus quantity, necessary when the sliding head lever roller 203 is passing down the cam surface 204 under the impulse of the steam or other pressure in the cylinder 124. Also considerable 95 more torque is necessary while the ejector cam roller 205 is raising the ejecting head, plunger and associated mechanism to eject 100

the block than at any other portion of the cycle of operation of the ejector cam.

The Whitney press, supplying great potential power to rotate the cam shaft, turned it at substantially constant speed during the entire revolution thereof, with the result that the entire cycle of operation of the press had to be kept at sufficiently low rate to avoid objectionable or destructive "slam" of the parts arising from excessive inertia in starting and stopping heavy parts during the movement thereof by the cam surfaces 201, 202 and 206, and especially during the movement of the sliding head by the cam surface 202.

15 The present invention provides for the application of greater force during the periods of movement of parts by the cam surfaces 201, 202 and 206 than during the remaining portion of the cycle of operation, and further 20 provides for a slower rotation of the cam-shaft during these periods than during the remainder of the cycle. I have thus provided correlated varying speed and varying power means effective during a single cycle of rotation of the shaft and during a single cycle of operation of the press.

I have also kept the momentum of the cam-shaft, parts rotating therewith and the prime mover to a minimum, thereby giving a construction which will stall without breakage in the event of any great resistance to rotation. Indeed, my improved drive discloses the initiation of any undue drag on the press operating parts, by unusual slowing down during the operation of the part presenting such drag, thereby enabling the operator to correct any maladjustment or the like before the condition has had time to do serious damage.

In the preferred embodiment of my invention selected for illustrative purposes, I have effected this by connecting a double acting steam engine 210, constituting a primary low inertia prime mover or power means, directly to the cam-shaft by a crank 211 having its crankpin 212 so positioned, rotatively considered, to the sliding head cam 108 that the engine 210 is on dead-centre at times when the sliding head cam is doing substantially no work, the dead centre at one end of the stroke being when the roller 203 is against the centric portion 213 of the cam 108, the sliding head being substantially at rest in mold-emptying position, and the dead centre at the other end of the stroke being when the roller 203 is against the centric portion 214 of the cam 108, the sliding head being at rest in pressing position. Incidentally, in the preferred embodiment of my invention shown, neither of these dead centres occurs while 55 the mold-emptying cam portion 206 of the ejector cam 136 is raising the mold plunger to empty the mold.

Thus, as shown in Fig. 3, the ejecting cam roller 205 has reached the centric portion 215, 60 to hold the mold plunger in elevated position,

a short period before the centre line of the crank 211 coincides with the centre line of the engine cylinder. The ejecting cam and its relation to cooperating cams are more fully described hereinafter.

As the crankshaft turns in clockwise direction, as viewed in Fig. 3, the roller 203 will next pass down the cam surface 204 with very little power from the engine, the turning impulse coming largely from the sliding head moving cylinder 124, constituting an auxiliary low inertia prime mover or power means, the piston of which is pressing the roller 203 against the cam surface 204 and hence tending to speed up rotation of the shaft during 80 this portion of its cycle.

Next, the centric portion of the cam 108, which lies between the cam surfaces 202 and 204, will pass relatively rapidly past the roller 203 during the filling of the mold, and the crank will be nearly at 90° from dead centre, in most advantageous torque-applying position during the operation of the cam portion 202 against the roller 203 to move the sliding head from mold-filling to pressing positions. 90 The effort involved may slow somewhat the rate of rotation of the cam-shaft, thereby preventing, when the press is operating at high speed, any tendency of the roller 203 to leave the cam (under the inertia of the sliding head and connected parts) when the point of the cam beyond the "rise" 202 is in line with the roller 203. While the centric cam portion 214 is against the roller 203, there may be gradual acceleration of the rate of rotation of the cam-shaft as the "rise" 201 approaches and first comes in contact with the roller 203 to start to move the sliding head from pressing to mold-emptying position, followed by a deceleration as the sliding head is moved 105 against the reduced back pressure maintained in the sliding head cylinder 124 during all portions of the cycle of operation of the press, excepting during the movement from mold-emptying to mold-filling position, 110 during which an increased pressure is admitted to said cylinder.

As clearly indicated by Fig. 4, the ejecting head 23 and attached mold plunger 25 are raised by the ram 2 for compressing the contents of the mold, and after the mold is uncovered are given an upward movement to eject the block from the mold. Following the ejecting of the block, the ejecting head is permitted to drop, the ram then (under normal 115 conditions) having descended to its lowest position. As in the prior Whitney press hereinbefore referred to, the cam shaft 66 may be provided with an ejecting cam 136 (Fig. 3) for raising the ejecting head and mold plunger to cause the latter to eject the block from the uncovered mold, as above explained. The mechanism for securing this result may take any convenient form, as for example, that used in the patented Whitney press, 120

comprising a roller 205 (Fig. 3) actuating the ejecting head lifting mechanism, so that when the roller 205 is depressed by the cam 136 the ejecting head will be raised, and when the cam permits the roller 205 to move upwardly the ejecting head will be permitted to drop. With the press operating as indicated by Fig. 4, the lifting of the ejecting head to eject the block is initiated during the descent 5 of the ejecting head with the ram, the descent of the ram caused by relieving the pressure exerted thereon by the fluid in the hydraulic cylinder 1, after the block is compressed. As the descent of the ram is in a sense controlled 10 by non-positive means (hydraulic pressure, and other factors hereinafter mentioned) it will be understood that in different cycles of operation of the press the ejecting head may be at different heights when its upward block 15 ejecting movement is to be initiated, and in consequence the portion of the surface of the cam 136 which first moves into contact with or "picks up" the roller 205 to initiate lifting of the ejecting head may vary for different cycles of operation of the press. 20

The operation of the ejecting cam 136, whereby the "rise" 206 presses down the ejecting roller 205 to lift the ejecting head and mold plunger (ejecting the compressed block 30 from the mold) takes place after the crank has passed its position of maximum torque and is completed as the crank approaches dead centre.

It is desirable that the ejecting operation 35 be effected as the crank approaches near to dead centre and at a time when the rotation of the cam crankshaft has been decelerated by the work of moving the sliding head into ejecting or mold-emptying position, so that 40 the ejection may be relatively slowly effected and accompanied by deceleration in the rate of rotation of the crankshaft as the ejecting operation approaches completion. The operation of the ejecting mechanism with the 45 camshaft rotating at a decelerated rate is particularly desirable because the point on the ejecting cam where the roller will effect the pick-up of the ejecting head, plunger and connected parts will, as hereinbefore explained, 50 vary considerably during the normal operation of the press in accordance with variances in the amount of relief (drop of the plunger and ejecting head pursuant to completion of the pressing operation) arising 55 primarily from slight differences in thickness of the blocks pressed, the amount of relief being a factor which it is practically impossible to control with any comparative degree of accuracy as compared with the 60 other important movements in the press cycle. In the ejecting cam shown in Fig. 3, the probable range of "pick-up" by the ejecting cam is indicated by the bracket 250, the usual point of pick-up being at the centre 65 thereof. Within this bracket 250, I have

therefore provided the most desirable pick-up velocity curves, the best curves being adjacent the centre thereof. It is, however, entirely possible that the pick-up may occur on any portion of the cam surface included 70 within the bracket 251.

The variance in proportional rate of rotation of the camshaft during different portions of the cycle thereof increases rapidly as the speed of the press is decreased. I have 75 taken advantage of this fact to provide very favorable pick-up curves on those portions of the cam surface within the bracket 250 and relatively undesirable pick-up curves at those portions of the cam within the brackets 80 206 and 252, thus providing a sufficiently favorable pick-up to admit of high speed of operation of the press under normal high speed operation, while obviating the likelihood of destructive shock when the pick-up 85 takes place outside of its normal range because the press is turning over at low speeds or for other reasons. Those portions of the pick-up within the bracket 252 come into operation when the pressing instrumentalities 90 are for any reason out of operation, or if, because of improper regulation of the drop of the plunger pursuant to an extreme increase in temperature of a batch of material fed to the press as compared with the temperature of a preceding batch, or for any other reason, a block is made of substantially greater thickness than that for which the ejecting cam is normally intended. Variations in relief occur in accordance with the speed of the 100 press, the relief being greater when the press is operating slowly than when operating rapidly, because greater time is then provided for the relief providing retraction of the fluid-actuated pressure-creating instrumentalities. Thus, when the press is operating unusually slowly, because of abnormally slow supply of material thereto, or for other reasons, the pick-up may occur at cam portions within the bracket 252 or in the adjacent cam 105 portions in the bracket 250. An insufficiency of liquid in the hydraulic cylinder or unusually low steam pressure on the pressing instrumentalities may also cause variations in the relief. In the press shown in the Whitney patent, the ejecting cam was designed to give an average velocity pick-up throughout the entire range of possible pick-up. In accordance with my invention, I have provided for substantially zero pick-up velocity at the 110 point of probable pick-up, viz, the centre of the cam portion included within the bracket 250, and have provided such gradual acceleration at each side of this point that the velocity pick-up within the bracket 250 is 115 everywhere fairly low, the velocity pick-up increasing as the probable frequency of pick-up decreases. In the brackets 206 and 252, I have provided for pick-up at greater velocities, but have kept them within the range of 120 125 130

practical operation even at maximum speed of the press, the decelerated rate of rotation of the camshaft during ejection being a decidedly helpful factor and permitting operation of the press at higher speeds than would otherwise be safe under the circumstances described.

The cams shown are adapted for making blocks of thicknesses from any desired minimum up to three inch, or even greater, thickness without change other than the change of ejecting cams. The ejecting cam illustrated is adapted for two inch blocks. For blocks of greater thickness, the cam portions 250, 206 and 252 should all be of somewhat less radius, the point of probable pick-up, however, being that of substantially zero acceleration, the acceleration curves at each side thereof becoming less and less desirable as pick up points in proportionately increasing degree as they are more and more remote from the point of probable pick-up.

The "fast flexible" coupling 221 is used not primarily as a universal joint, but to admit of fine adjustment of the relative position between the crank and the cams. This may be of advantage if for any reason it is desired to operate the press for a considerable period at slow speeds, slight movement of the 25 crank in contraclockwise direction giving an increased torque during the latter part of the sliding head moving operation of the cam-shaft and preventing possible "stalling" of the press by reason of the inability of the 30 engine to move the sliding head by the latter part of the operation of the cam surface 201, viz., that portion which is toward the cam surface 213.

If it were desired to make four inch blocks 40 on the press, I should probably avail of this adjustment to move the crank slightly in clockwise direction relative to the cams, as viewed in Fig. 3, primarily for the purpose of slowing down the rate of rotation during 45 operation of the ejecting cam. If, by reason of further refinements in the press, it were desired to speed it up to say fifty cycles of operation per minute, I should probably adjust the crank slightly in clockwise direction 50 relative to the cam, further to unbalance the engine and its points of greatest load to provide greater deceleration of the rate of rotation of the cam shaft during movement of the sliding head thereby and during the 55 operation of the ejecting cam.

The cams H⁶⁵ and L⁶⁵ operate while the sliding head is in pressing position to admit and exhaust steam from the elastic pressure fluid actuator for the hydraulic pressure applying instrumentalities, requiring but little torque to move the valves and overcome the opposed springs and pistons which keep their rollers H⁶⁵⁰ and L⁶⁵⁰ against their respective cams. Thus the pressing operation 60 requires substantially no power from the

camshaft turning instrumentalities and is not only independent thereof, aside from control, thereby reducing the torque which it is necessary to apply to the shaft and the likelihood of resultant trouble, but admits of the varied rates of rotation and varied torque which I have found so very advantageous in the operation of the press herein disclosed. Where the presses shown in the Whitney patent could operate at a rate of twenty-one to twenty-three cycles of operation per minute, I have found that with my improvements herein described the press can operate continuously at upwards of forty-two cycles of operation per minute. To provide for carrying the rotating parts past the dead centres of the engine and generally to steady the operation of the press, I have supplied a flywheel 220 which is relatively light and cannot at forty-two revolutions per minute accumulate sufficient momentum to prevent the desirable increases and decreases in speed of rotation of the camshaft. This arrangement substantially reduces the flywheel effect from that provided by the worm gear, worm and parts rotating with the worm shaft of the press shown in the Whitney press. I prefer, as illustrated, to connect this flywheel 220 to the camshaft and not directly to the engine crankshaft, thereby 70 protecting the relatively light engine and the "fast flexible" coupling 221 (hereinafter more fully described) from the inertia of the flywheel in case of sudden stalling of the press. The flywheel is preferably also at the 75 opposite end of the camshaft from the engine, thereby dividing on the camshaft the torque from the engine and the torque from the inertia of the flywheel.

The positioning of the flywheel also renders convenient the application of a spanner thereto, engaging the holes 222, if and when it is necessary to turn the camshaft by hand to get the press parts in proper position for starting, this being preferably the ejecting 105 position wherein the cams occupy the position relative to their rollers as shown in Fig. 3.

The cams used with my improved press preferably differ from those used on the press 110 when using the drive shown in the Whitney patent, in that the various portions thereof are moved or changed relative to one another to provide improved operation made possible by the varied rate of rotation, and in that, while the same sequence of operations is maintained, these operations are in some instances overlapped, the initiation of one operation sometimes preceding the completion of the preceding operation. Thus, I have shown in dotted lines (as distinguished from dashed lines) in Fig. 3 the form and 115 relative position of the cams as previously used on the Whitney press. By comparison of the two sets of cams, it will be observed 120

- that I have been able to cut down the number of degrees of the cam circle occupied by the pressing position curve 214, without correspondingly reducing the proportions of the cycle in which the sliding head is in pressing position, this because the relatively slow rate of rotation of the camshaft as the sliding head first reaches pressing position and the relatively slow acceleration as the crank 5 passes dead centre provide additional pressing time. The proportion of the number of degrees of the cam circle utilized by the head moving cam portions 201 and 202 have been correspondingly increased and the curves 10 and pitches thereof correspondingly modulated, without increasing the relative proportion of the cycle of operation available for these movements, because of the time saved by the accelerated rate of speed at which the 15 camshaft is turning when these cam portions first act on the roller 203. At the same time, the deceleration toward the end of these cam portions arising from slowing of the rate of rotation of the camshaft is availed of, as 20 previously herein stated, to prevent the roller 203 from leaving the cam under the influence of inertia when the movements thereof by the rises in the cams are substantially 25 completed.
- 30 In speeding up the press, I have found it possible to save portions of the cycle of rotation of the camshaft in some places, thus providing additional portions of the cycle in other places, this not only on account of the 35 varying rate of rotation and torque as heretofore explained, but on account of the "lag" of the operating parts. Thus, I have shown a set of cams wherein the ejecting cam starts to pick up its load (the ejecting head) before 40 the sliding head is completely in ejecting position, leaving the mold uncovered. I can do this because I can construct the ejecting head to take up the greater portion of the "relief" (provided by the pressing instrumentalities) 45 before the block will be pressed above the surface of the mold block. I also save considerable time by so constructing the portion 213 of my sliding head cam that the sliding head moves away from the mold during a substantial 50 portion of the ejection of the block therefrom. While this increases the extent of movement of the sliding head beyond that provided in the press shown in the Whitney patent, it provides a substantial extra amount 55 of the cycle available for deceleration of the sliding head and permits such deceleration to take place during the ejecting operation, thereby effecting a saving in the time cycle which is used to provide increased speed and 60 permitting more gradual deceleration and a better modulated ending of the cam surface 201, with resultant speed capacity in the entire cycle of operation. This construction of the cam portion 213 also permits me to start 65 the sliding head from mold-emptying to mold-filling position prior to completion of the mold-emptying operation, so that the curve for gradual acceleration of the sliding head during this movement may be of desirable form and so that the time normally 70 used for acceleration at this point may be saved for other portions of the cycle or applied to speeding up the press as a whole. Similarly the "rise" of the cam portion 202 begins somewhat earlier in the cycle than in 75 the previous press, the ejecting cam 215 releasing the ejecting head and mold plunger so that the drop thereof may start immediately before the sliding head reaches mold-filling position, the column of material in the mold-filling neck probably starting to drop momentarily later when the neck is in full register with the mold.
- Similarly, the low pressure cam L⁸⁵ opens its valve before the sliding head actually 85 reaches pressing position and the movement of the sliding head from pressing to mold-emptying position is started before the low and/or high pressure displacing plungers have returned to their non pressure applying 90 positions of rest, only very limited retraction of the mold plunger being sufficient to supply the relief necessary before the movement of the sliding head may be started.
- It will be understood that the crank connection between the cam shaft 66 and engine, and in fact the mechanical system presented by the engine-piston, connecting rod, crank and cam shaft, is mechanically reversible in the sense that the piston may be moved by 95 applying torque to the cam shaft and the cam shaft be moved by moving the piston. This construction results in an increased sensitivity of the engine to resistance to movement of the press parts, and affords a convenient means 100 for coordinating the forces impressed upon the press parts to the resistances offered by those parts.
- The double acting engine shown is of standard construction, except that it has no flywheel, its valves have no lead and it turns very slowly when the press is running at the present standard rate of 42 R. P. M. A governor 223 of standard construction, operated 105 by the usual belt 224, maintains the desired 110 average engine speed, the variations in such speed as heretofore described being evidenced by remarkable activity of the centrifugal speed actuated governor balls and cooperating 115 springs.
- Fig. 4 graphically illustrates in connection with the present example of the invention the coordination between speed, torque impressed upon the cam shaft, and the movements of the sliding head or mold cover, the ejecting head and ram during one cycle of operations. In this figure the upper curve shows the relative torque exerted on the cam shaft while the lower curve illustrates the 120 variations in speed of this shaft. The pe- 125
- 130

periods of various motions and rests of the sliding head, ejecting head and rams are indicated by the dimension lines and captions at the bottom of the figure. The abscissæ of both curves are "degrees of revolution" of the cam shaft or main cam 108. The ordinates of the lower curve are revolutions per minute. The ordinates of the upper curve are relative torque, the highest peak of the curve representing the maximum torque, the lowest depressions zero torque, and portions of intermediate height uniform percentages of the maximum torque.

The operation of the particular example of the invention hereinbefore described briefly is as follows. When the operation of the machine is to be initiated the engine, as hereinafter explained, preferably will be on that dead centre position which places the roller 203 on the first part of the drop 204 of the cam 108. Referring to Fig. 4, it will be observed that under these conditions the sliding head herein constituting the mold cover is in position to be moved to mold filling position. The steam supply to the engine may now be established, but, the engine being on dead centre, no movement of the cam takes place until the steam supply to the steam cylinder 124 is established. Upon establishment of this latter supply, the steam cylinder moves the sliding head to the left as viewed in Fig. 1 and causes the roller 203 to push on the cam 108 to cause the engine to rotate from dead centre position permitting the steam acting on the engine piston to move it.

From the foregoing it will be noticed that with the present embodiment of the invention if the engine is on dead centre and the operator fails to establish the steam supply to the steam cylinder 124, no movement of the press will take place. In the press constructed according to the Whitney patent, applying power to the cam shaft will cause it to rotate, but, if steam is not supplied to the steam cylinder 124, the roller will not follow the cam along the cam drop 204, and if then the steam supply to the steam cylinder should be established, the roller 203 will be violently projected against the cam with resulting damage to the machine. Conveniently the steam engine of the present embodiment of the invention is designed to stop in dead centre position when the steam supply thereto is interrupted and for reasons of safety will, for initiating operation, be cranked if necessary to the dead centre position above mentioned, from which it cannot be moved unless the steam cylinder 124 is in operative condition.

During operation of the particular machine described, the steam engine not only controls the application of the force of the steam cylinder 124 to the sliding head, but is accelerated thereby to secure increased speed when the steam cylinder is actuated, although

the force exerted by the engine is at that time relatively low. Thus the cam rapidly moves through its portion of revolution corresponding to the sliding head being at rest in the filling position, in which position the roller 203 is on the concentric portion of the cam between the cam drop 204 and cam rise 202 (Fig. 3).

The maximum torque exerted by the steam engine on its "crank end" stroke occurs as shown by Figs. 3 and 4 during the movement of the roller 203 up the cam rise 202 for moving the sliding head from filling to pressing position, the torque having decreased to a relatively low value, and likewise also the engine speed, as the sliding head comes to rest in pressing position. The engine torque is low while the sliding head is at rest in filling position, but again rises to reach a maximum during movement of the sliding head from pressing to block-ejecting position, the speed of the cam shaft decreasing to a minimum as the sliding head comes to rest in the last named position. When the sliding head is at rest in block-ejecting position, the ejecting head is moved by the cam mechanism to eject the block and at this time the engine speed is at its minimum and the torque rapidly falls to a minimum as the ejecting head comes to rest in its upper position.

In the particular embodiment of the invention herein disclosed it will be observed from Fig. 4 that the force impressed upon the cam shaft is relatively large when said shaft initiates movements of the heavy press parts, this high force condition continuing during the first or accelerating movements of said parts and decreasing during their final or decelerating movements, while it is a minimum during the portions of less movement of the parts and during their periods of rest. It will also be observed that in this embodiment of the invention the engine through its crank impresses upon the cam shaft a force of predetermined maximum limit regardless of the resistance opposed to said force, and further that the torque applied to the cam shaft varies from zero to a maximum and back to zero again through a half revolution of the crank.

The release of potential energy of the engine to the machine is limited and controlled by the crank in the same way as the force is limited and controlled. Thus the submitted embodiment of the invention includes a substantially low inertia or non-kinetic source of energy the release of which is coordinated and synchronized with the resistance offered by the heavy parts to be moved in such manner that unbalanced forces are a minimum. While the invention contemplates varying only the torque (force) applied to the cam shaft to secure a variation of energy during the cycle of operations for convenience in

the submitted embodiment of the invention the energy is varied by varying both the speed of the cam shaft and the torque.

As heretofore has been explained, the present embodiment of the invention employs an undersized flywheel, thus avoiding use of a power supply having a large amount of stored kinetic energy as in the ordinary reciprocating steam engine. Thus upon the occurrence of defective coordination of the movements of the machine parts or entry of a foreign body in each case tending to stop the operation of the machine, there is not available a supply of stored kinetic energy capable of being released to exert destructive forces upon the machine.

In the foregoing description, I have described what is shown by the drawings and what I have actually built and operated commercially. It is obvious that various changes may be made without departing from the scope of my invention. Thus hydraulic pressuring instrumentalities are merely a preferred form, the sliding head, cooperating stationary mold and connected actuating mechanism constituting merely a preferred construction for producing relative movement between mold and mold cover, the principles being identical if the mold moves instead of the mold cover, or, with respect to certain features of my invention, if both move. Various other changes may obviously be made without departing from the scope of my invention, which is best defined in the following claims.

Claims:

1. In a high speed press having a mold and a mold cover, actuating means for effecting relative movement between said mold and mold cover comprising a rotatable cam shaft and cam shaft rotating instrumentalities connected to said shaft and adapted normally to vary the rate of rotation thereof during different portions of the cycle of operation of said cam shaft.

2. In a high speed press having a mold and a mold cover, actuating means for effecting relative movement between said mold and mold cover comprising a rotatable cam shaft and cam shaft rotating instrumentalities connected to said shaft and adapted normally to vary the rate of rotation thereof during different portions of the cycle of operation of said cam shaft, said actuating means comprising a pressure fluid engine.

3. In a high speed press having a mold and a mold cover, actuating means for effecting relative movement between said mold and mold cover comprising a rotatable cam shaft and cam shaft rotating instrumentalities connected to said shaft and adapted normally to vary the rate of rotation thereof during different portions of the cycle of operation of said cam shaft, said actuating means comprising a pressure fluid engine having its

crank shaft directly connected to said cam shaft.

4. In a high speed press having a mold and a mold cover, actuating means for effecting relative movement between said mold and mold cover comprising a rotatable cam shaft and cam shaft rotating instrumentalities connected to said shaft and adapted normally to vary the rate of rotation thereof during different portions of the cycle of operation of said cam shaft, said actuating means comprising a pressure fluid engine having its crank shaft directly connected to said cam shaft at one end thereof and having a flywheel connected to said cam shaft at the other end thereof.

5. A high speed press having a relatively heavy part to be moved into various positions with intervening periods of rest, a cam shaft, a cam on said cam shaft for moving said relatively heavy part in one direction, a pressure fluid cylinder for moving said relatively heavy part in the opposite direction and a pressure fluid actuator for rotating said cam shaft under a greater potential torque when said cam is moving said relatively heavy part than when said pressure fluid cylinder is moving said part in the opposite direction.

6. A press having a sliding head, a cam shaft, a cam on said cam shaft for moving said sliding head in one direction, cooperating means for moving said sliding head in the opposite direction, and a pressure fluid engine having a crank operatively connected to said cam shaft, the angular relation between said crank and cam being such that said crank is in position to exert its most favorable leverage on said shaft when said cam is moving said head.

7. A press comprising, in combination, pressing instrumentalities, molding instrumentalities timed relative to said pressing instrumentalities but actuated independently thereof and automatically repeating actuating means for said molding instrumentalities adapted to vary in speed during different portions of each cycle of operation of the press.

8. A press comprising, in combination, pressing instrumentalities, molding instrumentalities timed relative to said pressing instrumentalities but actuated independently thereof and automatically repeating actuating means for said molding instrumentalities adapted to deliver different potential torques during different portions of a single cycle of operation of the press.

9. A press comprising, in combination, a mold and mold cover and actuating instrumentalities for relatively moving said mold and mold cover into three relative positions, for filling said mold, pressing the contents thereof and emptying said mold, respectively, said actuating means including a cam having a portion thereof shaped to effect

relative movement of said mold and mold cover during the emptying of said mold and to cause deceleration of the moving part to be completed while the mold is being emptied.

10. A press comprising, in combination, a mold and mold cover and actuating instrumentalities for relatively moving said mold and mold cover into three relative positions, for filling said mold, pressing the contents thereof and emptying said mold, respectively, said actuating means including a cam having a portion thereof shaped to effect relative movement of said mold and mold cover during the emptying of said mold and to cause accelerating of the moving part to be initiated while the mold is being emptied.

11. A press comprising, in combination, a mold and mold cover and actuating instrumentalities for relatively moving said mold and mold cover into three relative positions, for filling said mold, pressing the contents thereof and emptying said mold, respectively, said actuating means including a cam having portions thereof shaped to effect relative movement of said mold and mold cover during the emptying of said mold and to cause acceleration and deceleration, respectively, of the moving part to be initiated and completed, respectively, while the mold is being emptied.

12. A press comprising compressing instrumentalities, mold-covering instrumentalities and mold-emptying instrumentalities, automatically repeating actuating and timing means for moving said instrumentalities in desired sequence, said actuating and timing means providing for the initiation of at least one movement of the sequence prior to completion of the preceding movement thereof.

13. A press comprising molding instrumentalities, mold-emptying instrumentalities and automatically repeating actuating and timing means for moving said molding instrumentalities from closed mold to open mold position and for emptying the mold while in open mold position, said actuating and timing means providing for continued movement of the mold cover relative to the mold after open mold position is reached, such continued movement being utilized to decelerate the moving part even after initiation of the mold-emptying instrumentalities to eject the contents of the mold.

14. A press comprising, in combination, molding instrumentalities, mold-emptying instrumentalities and automatically repeating actuating and timing means for emptying the mold and for moving said molding instrumentalities from open mold to closed mold position, said actuating and timing means providing for initiation of movement from open mold to closed mold position prior to completion of the mold-emptying operation, such initiation of movement being utilized to accelerate the moving part even before

completion of the mold-emptying instrumentalities to eject the contents of the mold.

15. A press comprising, in combination, comprising instrumentalities, molding instrumentalities including a mold, a mold cover and a mold-filling neck, actuating and timing means providing for relative movement between said mold and compressing instrumentalities on the one hand and said mold and mold cover on the other hand, such movement providing mold-filling, compressing and mold-emptying positions, said actuating and timing means also providing for initiation of the cycle of operation of the compressing instrumentalities prior to completion of the movement from mold-filling to compressing position.

16. A press comprising, in combination, compressing instrumentalities, molding instrumentalities including a mold, a mold cover and a mold-filling neck, actuating and timing means providing for relative movement between said mold and compressing instrumentalities on the one hand and said mold and mold cover on the other hand, such movement providing mold-filling, compressing and mold-emptying positions, said actuating and timing means also providing for completion of the cycle of operation of the compressing instrumentalities after the movement from compressing to mold-emptying position.

17. A press having rotating means presenting a plurality of actuating means for press parts, an actuator for said rotating means adapted to rotate the rotating means at varying speeds during a single cycle of rotation thereof, said actuating means including a cam on said rotating means, said cam presenting operative portions spaced to compensate in desired degree for variations in the rate of rotative movement of said shaft during its cycle of rotation.

18. A press comprising, in combination, a relatively heavy part adapted to be shifted into three positions, a cam for actuating movement of said part into two of said three positions and pressure fluid means having connections with said cam including a crank presenting a favorable leverage for rotating said cam during said movement.

19. A press comprising, in combination, a relatively heavy part adapted to be shifted into three positions, a cam for actuating movement of said part into two of said three positions, pressure fluid means having connections with said cam including a crank presenting a favorable leverage for rotating said cam during said movement and means permitting adjustment of said crank relative to said cam to increase or decrease the unbalance between the pressure fluid means and its load.

20. A press having a rotating shaft for timing the operation of the press instrumentalities, a normally constantly operating pressure

- fluid engine operatively connected to one end of said shaft, a flywheel operatively connected to the other end of said shaft, said flywheel so proportioned with respect to its speed of rotation as to admit of substantial speeding up and slowing down of the rate of rotation of said shaft and engine during each cycle of rotation thereof. 5
21. A press including a mold, a mold plunger, mold emptying instrumentalities including a cam for moving said plunger into mold-emptying position and a normally continuously operating pressure fluid engine connected to operate said cam by connections including crank means which is substantially off its dead centre when said cam moves said plunger into mold-emptying position. 10
22. A press comprising a normally continuously operating actuator positively connected to operate the press parts and delivering substantially varying potential power to operate said parts during each individual cycle of operation of said press. 15
23. A press having a timing shaft for causing one cycle of operation of the press parts for each rotation thereof, and a prime mover delivering variable forces during each cycle of its operation for driving said shaft, said prime mover completing one cycle of its operation for each rotation of said shaft. 20
24. A press having a timing shaft for causing one cycle of operation of the press parts for each rotation thereof, and a double acting steam engine having its crank directly connected to said shaft. 25
25. A block press comprising, in combination, a mold, a mold cover and mold-emptying means, a cam organized and operating a part to uncover said mold to permit ejection of a completed block by operation of said mold-emptying means, said cam continuing to move said part in mold-uncovering direction after said mold is completely uncovered and during a portion of the ejection of the contents of the mold, such continued movement providing for cam-controlled deceleration of said part. 30
26. A press comprising, in combination, a mold and mold cover, a mold plunger reciprocable in said mold, a mold-filling neck, means for so moving said parts as successively to open the mold for mold-emptying ejection of the finished block, for bringing said mold and neck into register for filling of said mold from material contained in said neck, and for covering said mold during compression of the contents thereof, means for elevating said plunger when the mold is open for ejection and for dropping said plunger to or toward its mold filling position during movement of said parts from mold-emptying position to mold-filling position. 35
27. A press having a sliding head, a cam shaft, a cam on said camshaft for moving said sliding head in one direction, cooperating means for moving said sliding head in the opposite direction, and actuating mechanism including a power driven crank operatively connected in driving relation to said camshaft, the angular relation between said crank and cam being such that said crank is in position to exert its most favorable leverage on said shaft when said cam is moving said head. 40
28. A press having a mold, a mold plunger reciprocable therein, said mold plunger having a varying drop pursuant to releasing the pressure thereon after compression of the mold contents, and an ejecting cam for moving said plunger to eject the compressed contents of said mold, said ejecting cam presenting a favorable velocity pick-up at the portion of probable pick-up and adjacent portions in which the velocity of pick-up increases as the probable frequency of pick-up decreases. 45
29. A press of the character described having, in combination, a plurality of coordinated mechanical movements actuation of which is opposed by varying resistances, and low inertia power means for driving said press, said power means exerting upon said press variable actuating forces coordinated with and proportioned to said resistances. 50
30. A press having, in combination, mechanism presenting on one hand a relatively movable mold and mold cover and on the other hand a relatively movable mold and article ejecting head, and a low inertia prime mover capable of exerting upon the movable parts of said mechanism variable actuating forces coordinated with and proportioned to the resistances of said mechanism to movement. 55
31. A press of the character described having, in combination, instrumentalities actuation of which is opposed by variable resistances, driving means for the press including power and transmission means constructed and organized to impress upon said press limited variable forces synchronized with and proportioned to said variable resistances whereby said instrumentalities may be actuated at high speeds without occurrence of destructive inertia effects, said power and transmission means being of relatively low inertia whereby they are incapable of accumulating sufficient kinetic energy to be released in the form of destructive forces impressed upon said press. 60
32. A press of the character described having an intermittently movable, relatively heavy instrumentality; a low inertia fluid pressure actuated prime mover for actuating said instrumentality; said prime mover alternately delivering relatively high and low effort synchronized with the load imposed thereon by said press; means comprising an actuating shaft for moving said instrumentality. 65

tality; and a low inertia connection between said prime mover and shaft providing for exertion on said shaft of the high effort of said prime mover when it is moving said instrumentality and the low effort when it is stationary.

33. A press of the character described having a mold and mold cover, one of which constitutes a relatively heavy, movable part; 10 separate low inertia fluid pressure actuated prime movers respectively for moving said part in opposite directions; actuating and motion controlling means for said part; a mechanically reversible operating connection 15 between said means and one of said prime movers; connections between said part and the other of said prime movers and said means; said connection and means causing the first-mentioned prime mover to move said 20 part in one direction, the other prime mover to move said part in the opposite direction, and the last-mentioned prime mover when it moves said part to impart an accelerating force to the first-mentioned prime mover.

34. A machine of the character described having, in combination, mechanism of relatively high inertia to be moved through a cycle at variable speeds, low inertia power means for moving said mechanism constructed to deliver to said mechanism an actuating force which is decreased during the portions of the cycle when said mechanism has high kinetic energy and is to be decelerated.

35. A machine of the character described having, in combination, mechanism of relatively high inertia to be moved with periods of rest, low inertia power means for actuating said mechanism constructed to deliver to said mechanism an actuating force which increases as said mechanism is moved from at rest and decreased when said mechanism is moving and is to be brought to rest, said force being a maximum during movement of said mechanism and a minimum when said mechanism is at rest.

36. A machine of the character described having, in combination, a relatively heavy instrumentality to be moved through a cycle of operations with periods of rest, low inertia power means operative to deliver relatively high and low forces, transmission means connecting said power means to said instrumentality for causing motion of the latter, said power means impressing relatively low forces upon said transmission means when said instrumentality is at rest and relatively high forces when said instrumentality is moving.

37. A machine of the character described having, in combination, a relatively heavy instrumentality to be moved through a cycle of operations with periods of rest, low inertia power means operative to deliver relatively high and low forces, transmission means including a cam with concentric operating

portions connected by eccentric operating portions, said transmission means connecting said power means to said instrumentality for causing motion of the latter, said power means impressing relatively low forces upon said transmission means when said instrumentality is at rest and relatively high forces when said instrumentality is moving.

38. A machine of the character described having, in combination, a relatively heavy instrumentality to be moved through a cycle of operations with periods of rest, low inertia power means operative to deliver relatively high and low forces, transmission means connecting said power means to said instrumentality for causing motion of the latter, said power means impressing relatively low forces upon said transmission means when said instrumentality is at rest and relatively high forces when said instrumentality is moving, and power means independent of the first mentioned power means but coordinated therewith for at times augmenting the forces applied to said transmission means by said first mentioned power means.

39. A press having, in combination, a mold and mold cover, one of which constitutes a relatively heavy, movable part having a predetermined cycle of variable movement; a shaft presenting cam means for actuating said part during part of its cycle of movement and controlling the actuation thereof during the remainder of such cycle, actuation of said part by said cam means exerting retarding force on said shaft, and the controlling action of said cam means exerting accelerating force on said shaft; relatively timed but otherwise independent prime movers respectively for causing the cam actuated movement of said part and the cam controlled movement of said part, the prime mover for causing the cam actuated movement presenting a low inertial condition and variable torque drive in its cycle of movement.

40. A press having, in combination, a rotary shaft, a low inertia pressure fluid operated actuator having a mechanically-reversible, low-inertia, variable force transmitting connection to said shaft; a relatively heavy, movable part; means driven by said shaft for moving said part during a portion of the rotation of said shaft and permitting said part to remain stationary during another portion of said rotation; a second actuator for moving said part under the control of mechanism actuated by said shaft; the connection between said first-mentioned actuator and shaft providing a favorable leverage for the action of said primary fluid pressure actuator during movement of said part by said shaft, and an unfavorable leverage when said part is stationary.

41. A press of the character described hav-

- ing a relatively heavy part to be moved alternately in opposite directions with periods of rest; a relatively low inertia fluid pressure actuated prime mover capable of alternately 5 delivering relatively high and low effort at substantially constant frequency synchronized with the variable load imposed thereon by said press; cam mechanism actuated by said prime mover for moving said part in one direction; a second relatively low inertia prime mover for moving said part in the opposite direction; and said first mentioned prime mover being connected to said cam means to exert thereon its high effort during movement of said part. 10
42. A press having a mold and mold cover, one of which constitutes a relatively heavy, reciprocatory part, a low inertia prime over delivering predeterminately variable but 15 limited forces to a rotary shaft driven thereby, cam means on said shaft for moving said part from one end of its stroke to the other during a major fraction of one revolution of said shaft, and a second low inertia prime 20 mover exerting forces under control of cam means on said shaft for moving said part through its stroke in the opposite direction during the remaining minor fraction of said revolution and acting to augment the forces 25 applied to said shaft by said first mentioned prime mover. 30
43. A press having, in combination, means presenting on one hand a relatively movable mold and mold cover and on the other hand 35 a relatively movable mold and ejecting head, a rotary shaft arranged to actuate said parts through a cycle of operations during one revolution of said shaft, and a steam engine having two dead centre positions in one revolution provided with a crank substantially 40 directly connected to said shaft. 45
44. A machine having, in combination, a movable part, means including a rotary shaft for actuating said part through a cycle of operations during which said part opposes 50 rotation of said shaft with variable forces, a low inertia fluid pressure actuated prime mover, and a driving connection between the latter and said shaft presenting a crank substantially carried by said shaft. 55
45. A machine of the character described having, in combination, a plurality of co-ordinated mechanical movements actuation of which is opposed by varying resistances, and 60 a prime mover for driving said machine, said prime mover exerting upon said machine limited variable actuating forces coordinated with and proportioned to said resistances. 65
46. A machine of the character described having, in combination, a relatively heavy part to be moved through a cycle at variable speeds, primary low inertia power means for actuating said mechanism constructed to deliver to said part an actuating force which 70 is decreased during the portions of the cycle 75
- when the speed of said part is to be decelerated, and auxiliary low inertia power means for opposing the decreased force delivered by said primary power means during such deceleration of said part. 80
- In testimony whereof, I have signed my name to this specification. 85
